Primary Examiner — David G Muller(74) *Attorney, Agent, or Firm* — Thomas|Horstemeyer, LLP(57) **CLAIM**

The ornamental design for an enema bag, as shown and described.

DESCRIPTION

FIG. 1 is a perspective view of an enema bag, showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the drawings illustrate portions of the enema bag that do not form a part of the claimed design.

1 Claim, 5 Drawing Sheets(56)
